MEANS AND METHOD FOR OILING AND
MOISTENING COTTON

George Hill, Wellford, S. C.

Application May 8, 1931, Serial No. 535,995

17 Claims. (Cl. 19—66)

This invention relates to means and method for oiling and moistening raw cotton and other fibrous materials and is particularly adapted for use with machines used in manufacturing raw cotton and other fibrous materials into yarns or cloth in which form it is usually placed on the market. In machines and methods heretofore used in oiling cotton and other fibrous materials it has been difficult to have the oil penetrate evenly into the cotton or other fiber so that substantially all of the fiber was given the same amount of oil.

An object of my invention is to provide a device by means of which oil will be evenly distributed over the fiber and caused to penetrate evenly throughout the fiber.

A further object is to provide an improved pump for supplying the oil to the fiber.

A still further object is to provide a machine for moistening cotton or other fiber either in its raw state or after it has been converted into threads.

Further objects and advantages will become apparent as the description proceeds.

To simplify the description and to avoid needless repetition, the word cotton will be used but the machine is designed to treat any similar fibrous material, and should be so understood.

Referring to the accompanying drawings which are made a part hereof and on which similar reference characters indicate similar parts,

Figure 1 is a view in elevation of a cotton rolling machine of well known construction having my invention applied thereto,

Figure 2, a detail showing the connection of the oil supply with an air blast jet for spraying the oil upon the cotton,

Figures 3 and 4 are small detail views of two forms of jets or nozzles through which the oil is sprayed,

Figure 5 is a side elevation of a pump for delivering oil to the jets,

Figure 6, an end elevation as seen from the left of the pump shown in Figure 5,

Figure 7, a detail view showing mechanism for stopping and starting the oil pump,

Figure 8, a section on line 8—8 of Figure 7,

Figure 9, a modified form of machine used for adding moisture to cotton fiber, and

Figures 10 and 11 are modified devices showing different locations for the oil nozzle.

In Figure 1 is shown a machine of well known construction in which raw cotton is rolled into sheets. The cotton, generally after having been cleaned in previous operations, is delivered by

means of a conveyor 10 through rolls 11 to beater chamber 12 in which it is operated upon by beaters 13 which separate the fibers from the mass and straighten them as they are separated so that the fibers, after having been acted upon by the beaters, are in a highly divided state. The usual perforated grid 14 being positioned beneath the beater chamber 12. From the beater chamber the cotton is carried through a chamber 15, thence through rollers 16 and on through the machine. The other mechanism which engages the cotton forms no part of the present invention and therefore will not be described further.

My invention provides mechanism shown as a whole at 17 for delivering oil upon the cotton at 70 a point where it will most completely impregnate the greatest number of fibers of the cotton. This is at the point where the cotton is subjected to the treatment in the beater chamber 12 to separate and straighten the fibers. The mechanism 75 for supplying oil to the cotton will now be described.

This consists of an air manifold 18 to which air under suitable pressure is supplied from any suitable source. Attached to the manifold 18 are 80 outlet tubes 19 in the lower end of which are positioned nozzles 20. The nozzle 20 has a restriction at 21 and the outer end of the nozzle is slotted at 23 as shown in Fig. 3 or is provided with a number of small holes 22 as shown in 85 Figure 4. In either case the oil issues from the nozzle in a sprayed jet which is either in sheet form or in the form of a number of radially spreading jets. As shown in Figure 1, the ends of the nozzles are disposed within the beater 90 chamber 12 and are so positioned as to direct the spray of oil upon the cotton fibers at the point or points where they are acted upon by the beaters 13, so that the beaters not only separate and straighten the fibers but tend to mechanically distribute the oil over the fibers as they are separated. The tubes 19 are provided with oil connections at 24 to which oil pipes 25 are attached in any suitable way as by unions 26. Oil under pressure is supplied to each of the tubes 100 25 by means of a pump shown as a whole at 27. This pump consists of a number of pumping chambers each having an inlet and a discharge port. The inlet ports are connected to a common inlet manifold 28 to which oil may be supplied 105 in any suitable way. The outlets of the pumps are connected to pipes 25. The pumps are of the reciprocating type in which solid pistons operate. The pistons are all connected to a common operating head 29 which is guided upon suitable 110

guides 30 and 31. The head is operated by means of a link 32.

The means for reciprocating the pump pistons is shown in detail in Figures 5 and 6 and consists of an arm 33 pivoted to the frame of the pump at 34. To the hub of this arm is attached a short arm 35 to the outer end of which is attached the operating link 32. An arm 36 pivots on a shaft 37 on the frame of the machine and has on its lower end a gear segment 38. Secured on the other end of the shaft 37 is an arm 39 which is slotted and pivotally connected by means of a bolt 40 with the arm 33. The pivotal bolt 40 may be adjustable longitudinally of the arms 33 and 39 to provide means for varying the length of stroke imparted to the pump pistons. The gear segment 38 is operated by means of a train of gears 41, 42 and 43 in which a small pinion operates on a larger gear to provide speed reduction in a well known manner. The gears are driven by a pinion 53 operating on a pinion 44 which meshes with the gear 41. Pinion 53 is on the inner end of a shaft 45 on the outer end of which is a sprocket 46 over which operates a sprocket chain 47 which is driven by a sprocket 48 upon the outer end of a shaft on which roller 49 is mounted. The sprocket chain 47 is continuously driven. The pinions 53 and 44 are continuously driven, pinion 41 is movable axially to engage and disengage the pinion 44. The pinion 41 is mounted on a shaft 50 on the other end of which is a pinion 51 which engages with and drives the gear 43. The shaft 50 is movable axially to engage and disengage gear 41 from the gear 44 by means of a rocker arm 52 which is pivoted at 54 on the frame of the machine. A spring 55 engages the other end of the rock arm and tends to hold the gear 41 in mesh with the gear 44. These gears are moved out of mesh by means of a rod 56 on which is secured a collar 57 engageable with the end of the arm 58. The rod 56 is connected to a lever 59 by means of which it is operated, this lever being a well known part of a machine for rolling cotton of the type to which this invention is applied. A weighted arm 66 is provided for resetting the pistons when the clutch has been released. A stop 67 limits the backward stroke.

When the rod 56 is operated to control a clutch which controls movement of the cotton material the pump is stopped to stop the supply of oil being sprayed upon the top of the material.

Instead of placing the oil nozzle as shown at 17 in Figure 1 it may be positioned at the point X and as shown in detail in Figure 10 in which case the oil is sprayed upon the cotton in the chamber 15. In this position, however, the oil also thoroughly mixes with the cotton and so oils all of the cotton passing through the machine. Another advantageous position for placing the nozzle is shown on an enlarged scale in Figure 11 and shown in its relation to the machine at Y in Figure 1. In this position oil is delivered to the underside of the strip or lap of cotton entering the machine and just above the upper end of the grid 14. It is not contemplated to deliver oil at more than one of the three positions indicated. Should it be found necessary, however, the nozzles might supply oil at one, two or all of these positions if occasion seemed to require it.

In Figure 9 is illustrated a type of machine for supplying moisture to cotton in the form of threads in which the thread 60 passes over rollers 61 and 62 after it has undergone substantially all of its formative operations and passing out

through a relatively low tunnel 63 where water nozzles or jets 64 are positioned to deliver water upon the moving sheet of threads. The nozzle is preferably positioned to project water in the direction opposite to that in which the thread is moving, the thread, however, is thoroughly coated with a film of water and has the water evenly distributed over its surface. The nozzle 64 is that shown in detail in Figure 2 and the water supplied to the nozzle may be supplied by a pump similar to that which supplies oil to the oil nozzle. An air duct 68 is provided through which a blast of air is blown by a fan, not shown. This blast of air carries the moisture back into the tunnel and assists in distributing it evenly on the fiber.

In applying the water and applying the oil air under pressure is necessary. This air may be under relatively low pressure and in passing through the nozzle 19 it contacts with the oil entering from the port 24. In actual operation the oil issuing from the port 24 will tend to adhere to the sides of the nozzle 21. The velocity of the air issuing from the manifold 18 will tend to stretch out the oil film and the air issuing through the restricted nozzle 21 will tend to break up the stretched film of oil into a fine mist or spray. The oil is very thoroughly atomized by the air and is in fit condition to be sprayed as a fine mist out through the perforated or slotted nozzle 22 or 23. In any case the oil is rendered sufficiently fine to be sprayed evenly and thoroughly on the cotton in the machine.

It will be obvious to those skilled in the art that various changes may be made in my invention without departing from the spirit thereof and therefore I do not limit myself to what is shown in the drawings and described in the specification, but only as indicated by the appended claims.

Having thus fully described my said invention, what I claim as new and desire to secure by Letters Patent, is:

1. In a machine for rolling cotton and having a beater and a beater chamber, means for spraying oil upon the cotton in the beater chamber as the cotton fibers are separated one from another by the beater, said means being positioned adjacent the beater and comprising a plurality of nozzles extending into the beater chamber with means for supplying oil under pressure to the nozzles and means for supplying air under pressure to atomize the oil issuing from the nozzles, substantially as set forth.

2. In a machine for cleaning and picking cotton and other fibrous materials in the process of manufacturing yarns or cloth and other materials and having a beater and a beater chamber, means for spraying oil upon the cotton in the beater chamber as the cotton fibers are separated one from another by the beater, said means being positioned adjacent the beater and comprising a plurality of nozzles extending into the beater chamber with means for supplying oil under pressure to the nozzles, and means for supplying air under pressure to atomize the oil issuing from the nozzles, substantially as set forth.

3. In a machine for rolling fibrous material into sheet form and having means for stopping the machine after a predetermined quantity of such material has passed through, a beater chamber, a beater in said chamber for separating the fibers of the said material and an oil supplying nozzle extending into said beater chamber for spraying oil on the separated fibers at the points of beating, substantially as set forth.

4. In a machine for rolling cotton into sheet

form and having means for stopping the machine after a predetermined quantity of cotton has passed through, a beater chamber, a beater in the chamber for separating the cotton fibers and an oil supplying nozzle extending into said beater chamber for spraying oil on the separated cotton fibers at the point of beating, means for supplying pressure to the oil during the travel of the said cotton and for stopping the delivery of oil when 10 a predetermined amount of cotton has passed through the machine, substantially as set forth.

5. In a machine of the kind described having means for conveying a lap of cotton, a beater chamber through which the cotton is conveyed, a beater in said chamber adapted to separate the fibers from the lap, a grid beneath said chamber, and an oil supplying nozzle extending through said grid and directed to spray oil to the under side of the lap of cotton as it enters the beater chamber and is acted upon by the beater, substantially as set forth.

6. In a machine of the kind described having means for conveying a lap of cotton, a beater chamber into which the cotton is conveyed, a beater in said chamber adapted to act upon the lap of cotton as it enters the chamber to separate the fibers, a grid beneath said chamber, an oil supplying nozzle extending through said grid, and means for supplying air to said nozzle for atomizing the oil as it is delivered against the cotton, substantially as set forth.

7. In a machine of the kind described having a beater chamber, means for conveying a lap of cotton to the beater chamber and for delivering it into the rear of the chamber, means extending into the beater chamber for supplying a spray of oil upon the cotton in the chamber at the point of entry of the cotton therein, substantially as set forth.

40 8. In a machine for rolling cotton into sheet form, a beater chamber, means for introducing cotton fibers in mass-like form into said chamber, means in said chamber for separating the individual fibers of the cotton one from the other, and means for applying oil to the fibers in this separated condition in the beater chamber at the point of separation thereof whereby all of the fibers receive substantially an equal amount of oil, substantially as set forth.

50 9. In a machine for treating cotton, means for rolling the cotton into sheet form, a chamber having means therein for widely separating the individual fibers of the cotton, and means in said chamber for applying oil in a finely divided spray over the separated fibers at the point of separation whereby the separated fibers are given substantially an equal amount of oil, substantially as set forth.

10. In a machine for rolling cotton into sheet form, a beater chamber, means for introducing cotton fibers in mass-like form into said chamber, means in the chamber for relatively widely separating the individual fibers of the cotton one from another, and means for applying oil in a finely divided mist to the cotton fibers at the point of separation in the chamber and while the fibers are in a widely separated condition whereby the oil is evenly distributed throughout the cotton, substantially as set forth.

70

11. In apparatus for treating textile fibers, a beater chamber having an opening through which the fibers enter the chamber in mass-like form, rolls in said opening between which the fibers pass in entering the chamber, an oil nozzle extending into the beater chamber and directed to spray oil upon the fibers as they pass from between the rolls, a beater in the chamber adapted to act upon said fibers to separate and straighten the individual fibers and distribute the oil thereon, and means for operating said beater. 80

12. In the process of treating textile fibers to form thread, the step which comprises forcibly applying oil in the form of a fine spray to the fibers at the point of separation of the fibers from a mass in a beater chamber to insure the application of oil to the maximum number of separated fibers. 90

13. In the process of treating textile fibers to form thread, the successive steps which comprise continuously supplying the fibers in mass-like form to a beater chamber, separating the individual fibers from the mass as they enter the beater chamber, and spraying oil upon the fibers at the point of separation in the beater chamber to wet the individual fibers with oil. 100

14. In the process of treating textile fibers to form thread, the successive steps which comprise supplying the fibers in mass-like form to a beater chamber, effecting a separation and straightening of the fibers of the mass at the point of entry into the beater chamber by means of a continuously rotating beater, and forcing oil through a nozzle extending into the beater chamber directed to spray the oil upon the separated fibers at the point of separation thereof by the beater to insure the application of oil to the maximum number of separated fibers. 105

15. In apparatus for treating textile fibers, a beater chamber having an opening through which the fibers enter the chamber in mass-like form, rolls in said opening between which the fibers pass in entering the chamber, a beater in said chamber for separating the fibers from the mass as the mass enters the chamber, a grid below said opening, an oil nozzle extending into the beater chamber through said grid and directed upwardly to spray oil upon the fibers as they enter between the rolls and are separated by the beater, means for operating said beater, and means for forcing oil through said nozzle. 115

16. In the process of treating cotton fibers to form thread, the steps which comprise separating the fibers each from the others within a chambered member, and applying oil to the separated cotton fibers at the point of separation to insure the application of oil to the greatest number of separated fibers. 120

17. In the process of treating fibrous material, the steps which comprise introducing the fibrous material into a beater chamber, separating the fibers of said material each from the others in said beater chamber, and applying a moistening fluid to said fibers at substantially the point of introduction thereof into said beater chamber. 130

GEORGE HILL.
